FOOTREST STRUCTURE

Leon H. Gilson, Washington, D. C.

Application March 15, 1939, Serial No. 262,021

5 Claims. (Cl. 5—327)

This invention relates to footrest structure. It is aimed to provide a device of this character adapted for use primarily when reposing or even when seated and to be positioned by abutment against various objects, for instance, footboards or beds, other furniture, baseboards, and the like.

A prime object is to provide a novel construction which is adjustable to accommodate itself to the most efficient use and particularly so that it will be useful on beds whose mattresses project above the footboards.

I also provide a construction which is simple, inexpensive, has ample clearance for operation of the parts thereof, and one which may be folded compactly so as to occupy minimum space and permit portage in a suitcase or other receptacle.

Various additional objects and advantages will become apparent from a consideration of the description following taken in connection with the accompanying drawing illustrating an operative embodiment, by way of example.

In said drawing:

25 Figure 1 is a fragmentary side elevation of a bed, whose footboard extends above the mattress, showing my invention in use;

Figure 2 is a fragmentary side elevation of a bed, whose footboard terminates below the top of the mattress, showing my invention in use;

Figure 3 is a plan view of the invention alone;

Figure 4 is a cross sectional view, on an enlarged scale, taken substantially on the line 4—4 of Figure 3;

Figure 5 is a side elevation of the invention alone; and,

Figure 6 is an elevation showing the positioning bar and looking toward the inner face thereof.

40 Referring specifically to the drawing, wherein like reference characters designate like or similar parts, the invention has been illustrated in connection with beds A and B, as in Figures 1 and 2 respectively, by way of example only, and 45 it is to be understood that it may be used by abutment against objects generally, such as baseboards, and furniture.

In carrying out the invention, I provide a positioning bar 10 which may consist of a batten 50 of wood 11, preferably suitably upholstered, as at 12, which will not mar the surface or finish of a footboard, baseboard, furniture, or any other object against which it is adapted to abut. A metallic plate 13 is fastened along the inner surface of batten 11, as by means of screws or

other fastenings 14. Said plate 13 has an elongated slot 15 therein of any suitable length, and the batten 11 in communication with the slot 15 is recessed, as at 16.

A bolt 17 is slidably disposed in the slot 15 and it has a square portion 18 non-rotatably disposed in such slot. The bolt also has a head 19 which overlaps the inner surface of plate 13 and is accommodated in the recess 16. A winged or other nut 20 is screw threaded to the bolt 17 and the bolt between the winged nut and plate 13 passes through an angular end or lug 21 of an elongated, preferably flat, metallic rod 22.

A detachable footrest is shown at 23, which is preferably elongated and which may be of any suitable width. This footrest has a rigid body 24, which is preferably upholstered, as at 25, to any desired extent and in any preferred manner. It will be noted that the footrest 23 is disposed at a suitable angle and has a metal strip 23^a screwed thereto at 23^b which is detachably fastened as by means of a screw 23^c to a hook-shaped end portion 26 of an elongated, preferably flat, metallic rod 27.

The said rods 22 and 27 are slidably superposed so that the distance between the footrest and positioning bar may be lengthened or shortened, as is desirable according to the circumstances of use. To this end, a metallic strap 28 is fastened, as at 29, to the rod 27 and it surrounds the rod 22. Another metallic strap 30 is welded, or otherwise secured, to the rod 22. Such strap 30 surrounds the rod 27 and a winged screw or the like 32 is threaded in the strap and adapted to bind against the rod 27.

In using the structure, the positioning bar 10 may be arranged in contact or abutment with any suitable object adjacent to the user when reposing or even merely seated, and through the manipulation of the screw 32 and relative sliding of the rods 22 and 27, the footrest 23 will be disposed in the most advantageous position. As shown by Figure 1, the device may rest on the mattress or clothing of the bed A, designated 31, with positioning bar 10 in a horizontal position and abutting the footboard 34 above such mattress. The footrest 23 will be adjusted to the position most advantageous to the feet of the occupant of the bed.

In cases where the footboard of a bed, as at 35 in Fig. 2, does not extend above the mattress and clothing, the positioning bar is disposed at a right angle to the position of Figure 1, that is, in a vertical position, so as to project below the upper surface of the mattress and between the 55

footboard 35 and the mattress and clothing 36. The said positioning bar may be readily adjusted through the manipulation of the nut 20. Since slot 15 is elongated, the positioning bar may also 5 be disposed at a proper height.

Since the rods 22 and 27 collectively are of attenuated form and depend slightly below the positioning bar and footrest, they become embedded in the mattress and clothing of the bed, 10 which is a material aid in overcoming lateral slipping or displacement of the structure under pressure of the feet.

Various changes may be resorted to provided they fall within the spirit and scope of the 15 invention.

What is claimed is:

1. A structure of the class described having a footrest, a positioning bar generally parallel thereto, superposed rods, means connecting said 20 rods for relative longitudinal adjustment, said rods being disposed substantially centrally of the footrest and being attenuated so as to embed in a mattress or the like, one of said rods having a generally hook-shaped terminal angularly connecting to the footrest, the other rod having an upstanding end portion, said positioning bar having an elongated slot, and a bolt engaging said slot and connected to the upstanding end portion enabling variation of the position of the 25 positioning bar to facilitate engagement with dissimilar objects.

2. A device of the character described comprising a longitudinally adjustable bar having an upstanding arm at one end, a footrest mounted 30 at the other end of said bar, a positioning bar at the first end of said bar extending transversely thereof and including a batten having its inner face formed with a longitudinally extending pocket, a strip secured against the inner face of 35 said batten formed with a longitudinally extending slot opposite said pocket, a bolt having a head and a threaded shank formed with a squared portion, said bolt having its head disposed in said pocket and the squared portion of its shank passing through the slot of said strip and slidable longitudinally therein, the threaded portion of the shank being rotatably engaged through an opening in the arm of said bar, and a nut threaded 40 upon the shank and engaging said arm to releasably clamp said positioning bar in a set position and permit turning adjustment of the positioning bar from a horizontal position to a 45 vertical position and also permit longitudinal 50

adjustment of the positioning bar when the nut is loosened.

3. A device of the character described comprising a longitudinally adjustable bar having an upstanding arm at one end, a footrest at the other end of said bar and a positioning bar at the first end of said bar extending transversely thereof and including a batten, a strip secured against the inner face of said batten and formed with a longitudinally extending slot, a bolt having a shank formed with a squared portion passing through the slot and a threaded portion projecting from said strip and passing through an opening in said arm, and a nut threaded upon said shank to releasably clamp the positioning bar in a set position when tightened and permit turning adjustment of the positioning arm from a horizontal position to a vertical position and also permit longitudinal sliding adjustment of the positioning bar when loosened. 10 15

4. A device of the character described comprising a bar having an upstanding arm at one end, a footrest at the other end of said bar, a positioning bar at the first end of said bar including a member formed with a longitudinally extending slot, and a securing bolt having a shank formed with a flat-sided portion passing through said slot and a threaded portion passing through an opening in the arm and rotatable therein, said positioning bar lying in a plane transverse to the first mentioned bar and being turnable with the bolt as a pivot from a horizontal position to a vertical position when the bolt is loosened and also being slidable along the flat-sided portion of the shank transversely of the bar to an adjusted 20 25 30 35 position when the bolt is loosened.

5. A device of the character described comprising a bar having an upstanding arm at one end, a footrest carried by the other end of said bar and extending transversely thereof, a positioning bar at the first end of said bar including a member formed with a longitudinally extending slot, and a securing bolt having a shank passing through said slot and also passing through an opening in the arm and rotatable therein, means 40 being provided to hold the bolt against rotation in the slot, said positioning bar lying in a plane transverse to the first mentioned bar and being turnable with the bolt as a pivot from a horizontal position to a vertical position when the bolt is 45 loosened and also being slidable along the shank of the bolt to an adjusted position when the bolt is loosened. 50
